BATHING CAP

Phyllis Audrey Winnifred Davies, Otane,
Hawkes Bay, New ZealandApplication July 18, 1935, Serial No. 32,091
In New Zealand May 2, 1935

2 Claims. (Cl. 2—68)

This invention relates to bathing caps.

The object of the invention is to provide a cap which will exclude the water from entering the interior of the cap when in use.

5 According to the present invention, I provide a layer of sponge rubber on the inner side of the cap near the edge thereof, so as to bear upon the head of the person wearing it, while upon the exterior or interior of the cap in alignment with the layer of sponge rubber, I provide tunnel-like 10 passages through which a tightening element such as straps or tapes are laced, which may be tied and so tighten the edge of the cap and the layer of sponge rubber against the head of the wearer.

15 The invention will be described with the aid of the accompanying drawing, wherein:—

Figure 1 is an elevation of a rubber cap in which ear flaps are used.

20 Figure 2 is an elevation of a cap without ear flaps.

Figure 3 is a cross section of a portion of the cap on an enlarged scale.

25 Figure 4 is a view of the front of the cap shown in Figure 2.

Figure 5 is a cross section, and

Figure 6 is a fragmentary view of a modified form of the invention.

Referring to the drawing, on the inner side of 30 the cap 1 a layer of sponge rubber 2 is placed at or near the edge 3 or rim of the cap. On the exterior of the cap, opposite the layer of sponge rubber, tunnel-like passages 4 are provided through which tapes 5 are laced and adapted to 35 be tightened to press the layer of sponge rubber against the head and finally secured in the tightened position by tying.

In the case of the cap shown in Figure 1, these 40 tunnels 4 commence from a position behind the ear flap 6, shown in dotted lines for clearer understanding, and extend around the back of the cap to the other ear flap. The tunnels 4 on the front extend from in front of the ear flap to near the front of the cap, so that a space 7 will

be provided between the ends of the tunnels at the front and sides of the cap to enable the tapes 5 to project for the purpose of tightening them by drawing them forward, thus tightening the layer of sponge rubber around the head and then tying them at 8 as shown in Figure 4.

If a little water should leak through, or be absorbed by the sponge rubber at the point 9, it would be arrested at the pressure point of the 10 next tape.

In the case of the material of the cap being of material other than rubber, i. e., a water-proofed fabric, a construction as in Figures 5 and 6 may be employed. In this case, the layer of sponge 15 rubber is attached to the inner side of the cap by stitching, or by a rubber solution, or by a combination of both. In these figures the tunnels are formed by a piece of fabric 10 and stitched to the fabric 11 of the cap along the lines 12.

The piece of fabric 10 may, instead of being 20 stitched to the cap, be adhered by means of a solution and, if necessary, further strengthened by stitching as shown.

What I claim is:—

1. In a bathing cap, a layer of sponge rubber on the inner side of the cap around the inner circumference thereof, the lower edge of the layer coinciding with the lower edge of the cap, a pair of passages through the material of the cap immediately over the layer of sponge rubber, a pair of tapes threaded through the passages so as to bear upon the sponge rubber and enable it to be tightened against the head of the wearer in two places, the ends of the tapes extending out of the passages at the front of the cap so that they may be tied.

2. In the cap as claimed in claim 1, the passages extending from the front of the cap to a position close to the ear and continued from a position behind the ear around the back of the cap.

PHYLLIS AUDREY WINNIFRED DAVIES.
